[57] CLAIM

The ornamental design for a tire chain mounting facilitator, as shown and described.

DESCRIPTION

FIG. 1 is a perspective view of my tire chain mounting facilitator;

FIG. 2 is a top view thereof;

FIG. 3 is a bottom plan view thereof, it being understood that the raised knobs cover the entire bottom surface;

FIG. 4 is a front view thereof; and,

FIG. 5 is a right side elevational view thereof, with the left side elevational view being substantially a mirror image thereof.
